(54) **SAWING BOARDS**

(76) Inventor: **Ruel Jacobs**

*Kenel Jacobs, of Willton New York
Letters Patent*

*The Schedule referred to in these Letters Patent and making part of
the same containing a description in the words of the said Kenel
Jacobs himself of his improvement in the machine for sawing
Boards called the Economical Sawyer.*

*To all to whom these presents shall come - Kenel Jacobs, of the
Town of Willton, County of Saratoga and State of New York, sends
Greeting; - Be it known that I the said Kenel Jacobs have
Invented, constructed and applied to use, new and useful im-
provements in the sawing of timber, which are contained in a ma-
chine called by me the Economical Sawyer, and that the following
is a full and exact description of the construction and operation
of the said machine as invented and improved by me.*

*The objects proposed to be accomplished by the economical Sawyer
are to saw Boards and other timber without a steel shot and
to gauge the thickness of the board or other thing into which the
saw log is to be sawn, and to keep the saw log plumb while
it is being sawed. Construct a common head Block of the size
in all respects required by the size of the carriage, with the usual
gains on the upper and inside surface, and the usual grain or hoof
to receive the saw. When more than one saw is used at a time
in sawing it is necessary to have something to hold the inner
board up in its place, or the board which runs between the
saws, otherwise when it is sawed off, it will drop in the saw
gains of the head block and between the saws, and thus hinder the
return of the carriage. To prevent this the following piece of ma-
chinery is necessary. Dig one oblong mortise six inches in length, two
inches wide, and two inches deep on the inside of the head block.
Bring one or other of the sides, near the saw gains and between
the upper and under side of the Block. Let the length of the mor-
tise be parallel with the upper surface of the head block. Cut*

of wire of the size of number six or eight make a coiled spring, two inches in diameter and six inches in length. Place the spring lengthwise in the said mortise. Then take a piece of timber made the length of one of the said inside of the head block about three inches wide, and about one inch and a quarter thick, call this the slide or suspender. Let a piece of iron be wrought two inches in length, a little less than two inches in width and about a quarter of an inch in thickness. Let one end of it be turned up perpendicularly to the length of the said piece of iron so that the end turned up shall make a hook two inches long. Then turn the other end of the said piece of iron in the same direction and manner so as to make a similar hook one inch long. Let this piece of iron be turned at each end and be fastened on one of the broader sides of the said slide or suspender, parallel with the length thereof, and in the middle of the breadth thereof, and so that the said ends turned up or hooks shall project at right angles from the length of said slide, and so that the outside of the shortest hook shall extend to, and be even with, one end of the said slide.

Let the slide or suspender be placed on the said inside of the head block, in which the mortise was dug and the coiled spring placed lengthwise and parallel with the said inside so that the hook of the aforesaid piece of iron which is two inches long will pass into the mortise at the end of it nearest the rear gire in the head block, and returned and the end of the spring therein, and so that the other end of the slide or suspender be just even with the end of the head block next to the side of the carriage. Let two plates or slats be fastened on the said inside of the head block parallel with the length thereof, and far enough apart from each other just to allow the said slide or suspender to move back and forward horizontally between them. Let two or three straps fasten the said slide to the head block so it may slide under them forward and backward between the slats aforesaid according as the said slide may be moved by means herein set forth described. The said mortise must be so dug and the said

slid fastened at such a place as will bring the upper edge of the slide or support about an inch below the log resting on the gain of the head block. For the purpose of constructing the machinery to move the said slide or support, proceed as follows, at the end of the said inside, on which the said slide moves, that is, next to the side of the carriage and at right angles with the length of the said inside, dig a channel or gain about three inches deep and about three inches wide and along the whole length of the said end of the head block, so that the bottom of said channel shall be all the way perpendicular with and at right angles to the said slide. Out of some hard wood make a piece of timber about six inches longer than the length of the said outer width of the head block, and of a breadth and thickness easily fit into the said channel or gain, at the distance of about nine inches from one end of the said last mentioned piece of timber which may be called the lever, and on the side of the depth or thickness thereof, shave it equally and gradually to the point or end of the lever so as to make a regular step, and so that the end of the lever shall be about a half an inch in thickness. Make a piece of iron bar make wide about a quarter of an inch thick and an inch and a half longer than the length of the lever, fasten this lengthwise on the side of the lever opposite the shaven or sloped side, in the middle of that side, and so that one end of the said piece of iron shall project beyond the shaven end of the lever the distance of an inch and a half, let this be bent at right angles towards the face gain in the head block, and then bent again at right angles to the widest side of the slide, so that the piece projecting towards the slide shall be an inch in length, measured from the last bend or angle. This is intended to meet and act upon the hook upon the end of the slide nearest the side of the carriage. The lever must be fastened into the channel or gain in the end of the head block by a pin put through a hole bored through the sides of the gain or channel and through the lever parallel with the end of the head block, and at a distance of about

about one inch from the inside of the block piece and about an inch and a half from the end of the block piece. Then the result will be that the hook in the end of the lever, being caught upon the hook upon the end of the slide, that whenever the lever is pressed into the channel made for it the slide will be drawn back from the saw-gain. It is to leave that gain free from the passage of the saw, and when the lever is not pressed in, the slide will be under the saw log, so as to catch and hold the board when started off.

To push in the lever whenever the saw enters the saw-gain, let an arm made of wood be fastened upon the front post of the saw mill that shall just touch the lever and press it in whenever the block piece touches it, and which of course will cause to operate when the head block of the carriage has passed it, and which of course will leave the slide always under the saw log to hold up the boards or whatever may be stored, and will withdraw the slide whenever the saw enters the saw-gain. To construct the gauge and plumb necessary for sawing the thickness of the board and keeping the saw log plumb. At a point in the upper surface of the head block half way between the saw-gain and the end of the head block, and at a distance of about two inches from the gain for the saw log, fasten perpendicular and firmly a post about eight inches high, six inches wide and four inches thick, so that the broadest side shall be parallel with the length of the head block. Through the two broader sides of the post and in the middle thereof, and commencing at the surface of the head block, dig a socket three inches high and two inches wide so that the bottom of the socket shall be level with the surface of the head block and the upper side of the socket shall incline above the surface. Make a wooden belt or key about eight inches long, of a size to fit the socket on the upright post, tapering a little from one end to the other so as easily to get in and meddle and enough to fit after it is in. Then key or belt in for the purpose of fastening the plumb or gauge on

the required dimensions. The plumb or gauge is constructed as follows. Take a hard piece of timber two feet long, ten inches wide and four inches thick. At the distance of ten inches from one end saw through the width of this piece of timber perpendicular to within three inches of the opposite edge or side, then leave the piece which is ten inches in width and length and cut down the other. The whole of its length, as low down as the saw cuts, you will then have what may be called the plumb or gauge, and one part of it will be three feet two inches long, three inches deep and four inches wide with its upper surface smooth and parallel with its under surface. The other part of it will be of convenient inches square. Let the under corner of this square piece be cut off so as to prevent the saw dust from clogging the plumb. For the purpose of having a convenient place to put the boards &c when sawed crooked fasten a small post in the upper side of the gauge near the small end and of a height equal to the upper surface edge of the square or square end of the plumb. On the said upper edge of the square end and on the top of this post fasten a small bar or rail of convenient size and length. On this the sawed boards may be thrown while the saw you is sawing, until he can have time to remove them to other proper place.

The gauge or plumb is to be fastened on the gains of the head block which the saw log rests upon and parallel with the length of the head block and is fastened to any desired point by passing the key or bolt through the mortise in the upright post standing on the head block and over the plumb. By means of this boards or other stuff may be saved of any desired thickness. For the purposes of constructing dogs to hold the saw log in its position proceed as follows. Take a block of hard timber one foot and a half long and four inches square. On one side, being, and parallel with the length thereof fasten firmly a cast iron plate of equal length about one inch in thickness and two inches in width and let the ends of the plate be even with

the ends of the block of wood respectively. Make a cast iron slide about eight inches long and about three inches thick and about eight inches wide. Upon one of the wide sides of this let a groove or channel be cast, on which the plate on the top of a wooden block may be inserted, so that the slide or dog may move thence upon and the channel or groove must be deep enough to touch and hug the cast iron plate on the underside of the edges of it which extend over and beyond the sides of the wooden block so that the slide or dog may more easily backwards and forwardly, but not otherwise. Through this cast iron slide or dog let four or five holes be cast, and through the width thereof for the purpose of inserting wrought iron darts which may be drawn through them into the log to keep it fast, and may be easily taken out with an iron crow bar or mallet bar. These darts or spikes should be about an inch and a quarter square and about one foot in length. If it should be deemed necessary for the further security and steadiness of the log, two additional spikes of similar size may be put through holes, made and secured by iron cramps or otherwise, in the block of wood, on the iron plate of which the cast iron slide or dog, moves. These should be put as near that end of the block of wood which comes nearest to the tree as their firmness and the strength of the wood will allow, and cross directly above the other. This block of wood and its cramps complete the dog or slide, and must be fastened on the upper side of the head block and on that side of the tree which is opposite the one on which the plumb or gauge is fastened, lengthwise, straight and parallel with the length thereof so that the sides of the dog shall be in the same plane or surface with the upright or perpendicular side of the saw log grain, and the end of it must just touch the nearest side of the saw grain. Let this end be the one in which the additional spikes or darts are inserted. The wooden edge of the inside of the slide or dog should be cast with small eyes so as to fit a small cast iron wheel.

to be placed below it, with a couple to be inserted through the block of wood for the purpose of turning the slide or dog backwards, or forwards as occasion may require, and the under edge of the other or outer side of the dog is to be notched to receive a catch or hand to be fastened to the said block of wood to keep the slide or dog from going back or moving when set.

Another kind of plumb or gauge may be made in lieu of the one just now described, by fixing a slide in the same manner as last described, except the spears on the same side when the other plate was placed by fastening a small iron plate about six inches long, four inches wide and an inch thick onto the inside of the gauge, and at that end of it which is next the saw-gain and perpendicular to the inside of the slide. The length of this small plate is to be up and down. The wooden block on which the slide moves to be placed in the same position as the dog only on the opposite side of the saw-gain. This slide may be made to move so as to detect the thickness of the stuff to be sawed at will. The whole head block is intended to be movable at pleasure, in order to meet and provide against the difference in length of the timber to be sawed. For this purpose a couple or more of strong iron hooks are fastened firmly to each end of the head block to hang down and catch in a cleat to be fastened on each out side of the carriage at such places therein as may put the head block in a proper position as required by the length of the timber to be sawed. A foot block similar to the head having a saw-gain to allow the saw to saw through the log, and having upon it all of the machinery herein above described, except the spring, slide and lever and hooks, is to fasten firmly upon the foot or other end of the carriage. The machinery is then complete for sawing boards and other stuff without stick stuffs - for gauging the thickness of the stuff intended to be sawed, and for keeping the log plumb and for fastening the log in its proper place. The machinery

for three several purposes may be used separately or together,
as may be thought best, as either may be used without the other,
and the improvements for each purpose as hereinabove set forth,
the said Inventor fully claims as his - In witness whereof,
he hath hereunto set his hand and seal this 11th day of Sept
ember in the year of our Lord One Thousand Eight hundred
and Ninety.
